GRANT SIPP, OF PATERSON, NEW JERSEY, ASSIGNOR TO SIPP EASTWOOD CORPORATION,
OF PATERSON, NEW JERSEY, A CORPORATION OF NEW JERSEY

WARPING MACHINE

Application filed November 6, 1928. Serial No. 317,650.

This invention relates to warping machines and in particular to the means for controlling the reel of such machines. The present improvements have for their principal objects the following, to wit, (1) to have the reel entirely free of any braking action while the power to rotate the same is on and subject it to such braking action when the power is cut off, and have such braking action when applied bring the reel smoothly or in eased fashion to a stop, thus to insure on such stopping that the warp threads be kept taut between the reel and the spools on the creel from which they are drawn, and in this connection also to provide for adjustment of the braking pressure to suit different speeds at which the reel may be driven or permit the reel when rotated at a given speed to continue rotating a more or less distance, as the operator may wish, after the inception of each brake-application; (2) to provide for locking in the working position the means for applying the power to the reel so that the machine will continue running alone, or without effort on the part of the operator; (3) to provide for locking the braking means in idle position so that the reel is free for manual rotation as the operator may at times require; and (4) to accomplish these various objects by mechanism which is simple in construction as well as reliable and efficient.

In the drawings, Fig. 1 is a side elevation of a warping machine embodying the present improvements;

Fig. 2 is a left-hand end elevation of the machine, the reel and certain other conventional parts being omitted;

Fig. 3 is a fragmentary side elevation, partly in section, of the parts directly involved in the invention;

Fig. 4 is a plan, partly in section, of a detail of Fig. 3;

Figs. 5 and 6 are elevations of certain parts in Fig. 3 as seen from the right and left, respectively;

Fig. 5a is a plan of parts appearing in Fig. 5.

Figs. 7 and 8 are sections on lines 7—7 and 8—8, respectively, of Fig. 2; and

Fig. 9 is a front elevation of Fig. 8, partly in section.

In a frame 1 of the supporting structure is journaled the reel 2 having a concentric rim 3. Means to apply driving power to the reel is afforded by the rotary driver 4 (here driven by belt 5 from any going pulley) movable into or out of peripheral contact with the wheel rim by lever 6 fulcrumed at 7 between its ends and connected with a treadle lever 8 by a link 9, lever 8 being held normally elevated (so that the driver is clear of the rim) by a spring 10, an arm 11 on said lever then abutting the frame as a stop. So much is usual and well known. 55 60 65 70 75 80 85 90 95 100

13 is a brake-band extending around rim 3 and supported by the means 14 and 15 (carried by the frame and forming parts of the supporting structure as a whole) so as to be capable of being tightened or slackened substantially as in my Patent No. 1,657,044; it includes a stiff metal strip having a leather lining 13a.

When beaming is being done the brake-band is tightened to impose a drag on the reel so that the warp will be wound tightly on the beam. Heretofore for the warping operation the brake-band was for the time being usually slackened but so that it still afforded the resistance required for stopping, remaining, however, active as well when the power was on as when it was cut off, so that waste of power and wear of the 85 90 95 100

brake-band and wheel-rim were consequent results and it was further difficult in setting the strap to adjust it so as to complete the stopping action, regardless of the speed of the reel, in a predetermined interval after inception of the stopping or braking action. By the present invention I avoid these consequences and attain the other advantages hereinbefore pointed out.

An elongated bracket 16 projects from the frame 1 in radial relation to the reel, preferably horizontally, being provided with a block 16a (Figs. 3 and 4) which is secured to the bracket by a bolt 16b and coacts with an offset 16c of the bracket to form a clamp.

gripping a flange 1a of the frame. In the free end of the bracket is a fulcrum pin 18 for a lever 17 (bifurcated in plan, Fig. 5a) having upwardly and downwardly extending arms 17a and 17b and a presser arm 17c which is bent toward the outer face of the brake-band and preferably has its terminus convex, the fulcrum 18 of said lever being parallel with the axis of the reel. To reinforce bracket 16 there may be a brace 15a connecting parts 15 and 18 as shown. Arm 17a is connected by a spiral spring 19 with a threaded stem 20 penetrating freely an upstanding arm 16d on the bracket and having a nut 20a and also a lock-nut 20b screwed thereon. Arm 17b has an extension 17b' adjustable around the pivot at 17b'' by virtue of the slot-and-bolt clamping means at 17b''. A staff-like crank 21 up 10 stands rigidly from the fulcrum portion of the treadle-lever. Pivottally connected at its rearward end to extension 17b' and supported at its forward end as hereinafter stated is a link 22 having an abutment 22a forward of and adapted to be engaged by crank 21 when the treadle lever is depressed. For warping the brake-band is adjusted so that of itself it would oppose no appreciable resistance to the rotation of the reel, but the 15 lever 17 is normally held by spring 19 with its arm 17c pressing the brake-band against the reel-rim so that in a limited region, only, of itself the brake-band is made normally to apply localized braking pressure to the reel. 20 When, however, the treadle lever is depressed to drive the reel, its crank, acting on the link at 22a, retracts the lever 17 against the tension of the spring, freeing the reel. Thus, with the treadle lever depressed 25 to apply the power the brake is released, and with the treadle lever elevated, cutting off the power, the brake is set. The braking pressure is determinable at will by adjusting the tension of the spring at 20a, 20b. An important feature of this part of my invention is the application of the braking pressure to a localized part of a brake-band as distinct from exerting a pull on the band to constrict it to the braking surface 30 afforded by some appropriate peripheral surface of the reel, as rim 3, or utilizing a brake having its braking face concave and fitting such surface, either of which is in practice entirely unsuitable because it in 35 variably produces an intermittent binding and hence hesitating stopping which causes the warp threads to be left more or less loose between the reel and creel when the stopping is completed. Since the arm 17c 40 presents a pressure surface of limited area to the brake-band the effect is to bend the latter inward from its normal state against the reel rim so that only a limited region of the band is in fact active to exert pressure 45 on the rim, and this gives an eased or grad-

ual and non-intermittent stopping not otherwise possible.

A revoluble shaft or bar 23 is journaled in the ends of the sides of the frame structure and has affixed thereto at the far end in Fig. 1 a crank 24 and at the near end a crank 25, the whole forming what I term herein a shifter. Crank 24 forms one element of a toggle-connection between shaft 23 and the treadle lever the other element of which is a link 26 which is pivoted to the crank at 24a and has a longitudinal slot 26a receiving a stud or pivot 8a on the treadle lever, the upper end of the link projecting upwardly beyond pivot 24a and forming a bunter to impinge against the shaft 23 when the crank has been turned anti-clockwise in Figs. 1, 4 or 7 until the pivot 24a has passed a plane coinciding with the axis of the shaft and pivot 8a. When the shifter is so turned it acts through 24-26 to depress the treadle against the tension of spring 10 and becomes toggle-locked in the new position (dotted lines, Fig. 7), and in this position of the part the power is applied and the braking pressure removed so that the machine will continue running unattended until the toggle-lock is disestablished, which may be effected by turning the shifter clockwise either by hand or pressing suddenly on and then releasing the treadle so that pivot 24a returns past the mentioned plane.

The crank 25 has two arms 25a and 25b which in the idle position of the mentioned shifter depend vertically. One of these, 25a, is forked and receives the forward end of link 22, having a pin or bolt 27 penetrating a longitudinal slot 22b of the link. The other, 25b, has a latch 28 which is spring-pressed against a boss 29 at the inside of the adjoining side of the frame structure 1 and has its acting end (the one engaging the boss) tapered and adapted to enter a tapered notch 29a in the periphery of the boss when said shifter has been moved from its said idle position clockwise so that said crank stands in the dotted position of Fig. 3. The beveling incident to tapering the latch and notch permits the lock thus established to be forcibly disestablished by turning the shifter back or anti-clockwise by hand.

When the shifter is locked in the position last described its pin 27, acting against the outer end of slot 22b, acts to hold link 22 shifted to the left in Fig. 3, so that the brake is released; the reel is thus free to be rotated directly by hand.

Slot 26a is present in link 26 to permit the shifter to move clockwise to latched position (to act, through link 22, to hold the brake released) independently of the treadle lever, then fully elevated.

To recapitulate: The shifter may assume either of the three positions I, II and III designated in Fig. 3. In position I the

shifter is idle and whenever the operator depresses the treadle lever the reel will be rotated and whenever the treadle lever is allowed to rise the reel will be stopped. In position II the treadle will be locked down, acting through 21-22 to hold the brake released and through 9-6 to apply the power. In position III the brake is held released by the shifter, so that the reel is free to be rotated by hand or by power through the treadle. In other words, the shifter and link 26 constitute movable controlling means—of which shaft 23 forms a hand-grip-controller—movable to one position to lock the power-applying means in the position for applying the power and retracting the braking means and to the other position to lock the braking means in retracted position; and, further, in an intermediate position in its range of movement said controlling means is inactive to perform either of these functions, so that both the braking and power-applying-means remain operative and cooperative in the manner described subject 20 to the influence of the actuator afforded by the treadle lever.

Slot 22b is present in link 22 to permit the link to move forward when treadle-operated with the shifter in position I and also 30 to permit necessary lost-motion between the shifter and link when the shifter in being moved anti-clockwise to toggle-locked position II causes depression of the treadle and consequent brake-releasing motion of the link as explained.

Having thus fully described my invention, what I claim is:

1. A warping machine comprising, with a supporting structure and a reel journaled therein and having around its axis a braking surface, means to apply braking resistance to said surface including a brake-band supported by said structure with a portion thereof in face to face relation to said surface, and means to press said portion against said surface having its pressure surface of relatively limited area.

2. A warping machine comprising, with a supporting structure and a reel journaled therein and having around its axis a braking surface, means to apply braking resistance to said surface including a brake-band supported by said structure with a portion thereof in face to face relation to said surface, and means to press said portion against said surface having its pressure surface of relatively limited area and convex.

3. A warping machine comprising, with a supporting structure and a reel journaled therein and having around its axis a braking surface, means to apply braking resistance to said surface including a brake-band supported by said structure with a portion thereof in face to face relation to said surface, a pressure member movable to press

said portion against said surface and having its pressure surface of relatively limited area, means to supply driving power to the reel and means common to said pressure member and the last-named means for controlling them.

4. A warping machine comprising, with a supporting structure and a reel journaled therein, means movable to apply driving power to the reel including a treadle for effecting such movement of said means, and a toggle-lock connection extending upwardly from the treadle to said structure and having one member revoluble in the latter and comprising a horizontal axial hand-grip controller.

5. A warping machine comprising, with a supporting structure and a reel journaled therein and having around its axis a braking surface, braking means movable to and from and normally urged against said surface to apply braking resistance to the reel, means movable to apply driving power to the reel and simultaneously retract the first means, and means movable independently of the second means against and thereupon adapted to lock the first means in retracted position.

6. A warping machine comprising, with a supporting structure and a reel journaled therein and having around its axis a braking surface, braking means movable to and from and normally urged against said surface to apply braking resistance to the reel, means movable to apply driving power to the reel and simultaneously retract the first means, and means movable independently of the second means against and thereupon adapted to lock the first means in retracted position including a controller revoluble in said structure.

7. A warping machine comprising, with a supporting structure and a reel journaled therein and having around its axis a braking surface, braking means movable to and from and normally urged against said surface to apply braking resistance to the reel, means movable to apply driving power to the reel and simultaneously retract the first means, and means movable against and thereupon adapted to lock the first means in retracted position including a horizontal hand-grip controller shaft revoluble in said structure.

8. A warping machine comprising, with a supporting structure and a reel journaled therein and having around its axis a braking surface, braking means movable to and from and normally urged against said surface to apply braking resistance to the reel, means movable to apply driving power to the reel and simultaneously retract the first means and controlling means movable to one position to cause the second means to undergo such movement and to another position

to cause the braking means to undergo reTRACTING movement.

9. A warping machine comprising, with a supporting structure and a reel journaled therein and having around its axis a braking surface, braking means movable to and from and normally urged against said surface to apply braking resistance to the reel, means movable to apply driving power to the reel and simultaneously retract the first means and back-and-forth movable controlling means movable in one direction to cause the second means to undergo such movement and in the other direction to cause the braking means to undergo reTRACTING movement.

10. A warping machine comprising, with a supporting structure and a reel journaled therein and having around its axis a braking surface, braking means movable to and from and normally urged against said surface to apply braking resistance to the reel, means movable to apply driving power to the reel and simultaneously retract the first means and back-and-forth movable controlling means normally occupying a position where it is inactive on either the braking or second-named means but movable therefrom in one direction to cause the second-named means to undergo movement to apply driving power to the reel and retract the first means and in the other direction to cause the braking means to undergo reTRACTING movement.

35. In testimony whereof I affix my signature.
GRANT SIPP.
